UNITED STATES PATENT OFFICE.

SAMUEL GARVIN, OF CUSTER, MONTANA.

ENDLESS WATER-CONVEYER.

No. 895,250.

Specification of Letters Patent.

Patented Aug. 4, 1908.

Application filed March 16, 1908. Serial No. 421,339.

To all whom it may concern:

Be it known that I, SAMUEL GARVIN, a citizen of the United States, residing at Custer, in the county of Yellowstone and State of 5 Montana, have invented certain new and useful Improvements in Endless Water-Conveyers, of which the following is a specification.

This invention relates generally speaking to endless bucket conveyers for general use 10 and especially to a conveyer of this type designed for the elevation of water for irrigating and other purposes.

The invention consists of certain specific details of construction which will be herein- 15 after fully described and illustrated on the accompanying drawings in which,

Figure 1 is a side elevation of the invention, shown in operative position; Fig. 2 is a fragmentary rear elevation of the same; Fig. 20 3 is a diagram of the blank from which the bucket is made; Fig. 4 is an end view of a bucket; Fig. 5 is a detail of one of the chain links, and Fig. 6 is a detail of a valve in the bottom of the bucket.

25 Throughout the following description and on the several views of the drawings similar parts are referred to by like reference characters.

In the preferred embodiment of the invention the same includes a tower 10 of any suitable construction and dimensions. As indicated the tower 10 comprises substantially vertical uprights 11 and 12, the uprights being suitably connected and braced by a bottom member 13 and a top frame member 14. 30 The tower 10 is adapted to be supported upon any sort of a support, such as a trolley, boat, or the like, such supporting device not being illustrated inasmuch as the same constitutes no portion of the present invention. 35 For convenience of description the uprights 11 will be considered as defining the front of the machine, and the uprights 12, the rear of the machine.

40 45 Journaled transversely of the tower at or near the lower rear corner is a shaft 15 carrying near each end an idler sprocket wheel 16. Likewise at the upper and rear corner of the tower 10 is a shaft 17 having at its ends sprocket wheels 18, each wheel 18 lying in the same vertical plane as the corresponding wheel 16. Again, at the upper front corner of the frame is a power shaft 19 having sprocket wheels 20 in the planes of the afore- 50 55 said sprocket wheels. The shaft 19 furthermore carries at its ends drive sprocket wheels

21. Operating over each set of sprocket wheels 16, 18, and 20 is a chain belt 22 of any suitable or approved construction, preferably, however, of the detachable link type. The 60 chains 22 therefore operate in parallel planes and are of substantially the same length.

In order to provide a certain amount of adjustment in the length of the chains 22 any one or more of the shafts supporting the 65 same may be mounted in adjustable bearings. As indicated the shaft 15 is mounted in a bearing 23 whereby the shaft 15 may be raised or lowered as may be necessitated by usage. This shaft and the parts connected 70 therewith are supposed to be located at or below the surface of the body of water to be elevated.

Connected to and suspended between the chains 22 is an endless series of buckets 24. 75 These buckets may be connected to the chain by any suitable devices, but preferably they are connected rigidly to elements of the chain whereby they are prevented from having movement independent of the movement of 80 the chains, in other words there is no pivotal or other movement of the buckets with relation to the lines of the chains. By this means each bucket has a fixed position with relation to the plane of the two opposite portions of the chains to which the bucket is attached. As a suitable and convenient, as well as a cheap means, for thus securing the buckets to the chains there are provided special links 22' one of which is secured to 85 each end of a bucket. Each link 22' has a usual body portion corresponding to the usual chain links whereby the link 22' cooperates with the sprocket wheels 16, 18, and 20 in the same manner as the other links. The inner 90 bar, however, of the link is provided with ears 22'' which lie in the same plane and at right angles to the said bar. Preferably said ears extend on opposite sides of the vertical plane of the link.

100 Each bucket 24 may be of any construction adapted for the purpose of the invention, preferably, however, made of sheet metal and from a single blank in order to increase the strength, durability, and cheapness of the 105 same. As plainly indicated in the drawings the blank comprises a number of features, and when made up into a bucket the features or elements *a*, *b*, and *c*, at each end of the bucket overlap one another for the purpose of adding strength at the particular point where 110 the point of attachment of a link 22'.

The ears 22" of a link lie against the outer face of one of the said elements, indicated as *c*, and securing means such as rivets pass through all three of said features, securely fastening the link to the bucket and assisting in firmly securing the parts of the bucket together. These parts are furthermore secured by additional means such as brazing so as to make the bucket water-tight, the other portions of the blank indicated by the letters *d*, *e*, and *f* constitute a back, front, and bottom, respectively, said last mentioned members being rectangular.

Considering the open portion of the bucket as the top, the top or upper edge of the back *d* always leads and the bucket preferably is secured to the chains 22 so that the upper edge of the back and the inner edge of the bottom lie in a plane substantially parallel to the plane of the chains. By this arrangement it will be seen that when the bucket is supplied with water the bulk of the water will lie largely below the plane of the connected links, and that the bucket will be almost entirely filled with water. As the bucket is carried upward over the shaft 17 the bucket will tilt gradually, and the contents thereof will be emptied into a chute *S*, the projecting lip at the forward edge of the bucket back preventing any premature spilling and loss of water. The trough or chute *S* will therefore receive the water from the buckets as they pass successively over the shaft 17 and convey it away to any suitable or preferred place of deposit or use, as for instance for irrigation purposes.

Inasmuch as the buckets are carried downwardly into the source of water supply with the open portions downward it has been found desirable to provide each bucket with one or more automatically operating valves, whereby the air contained in the empty buckets and which would require an unnecessary expenditure of power to force the buckets downward into the water, may escape. As a suitable illustration of such valves there is provided in the bottom of each bucket a hole 25 through which projects loosely a bolt or plunger 26 having on the outside a head 27 and on the inner end a nut 28. Adjacent to the nut 28 is a washer or gasket 29 which together with the bolt constitutes a valve. The inner face of the head 27 is provided with a plurality of projections 27' which may contact with the bottom of the bucket and prevent any possibility of the said head 27 closing the hole 25 when the bucket is inverted, at which time the air must have free exit. As the bucket enters the water the air contained therein will pass freely out through the hole 25 and between the head 27 and the bottom of the bucket. As the bucket turns about the shaft 15 the position of the valve

will automatically change and by the time the bucket is filled with the water the gasket 29 will be seated against the bottom of the bucket, substantially closing the hole.

The mechanism thus far described may be operated by any suitable power or hand devices, depending upon the capacity of the machine. As a suitable illustration of such power devices there is indicated a transverse shaft 30 journaled on suitable brackets preferably within a triangle determined by the chain belts 22. At each end of said shaft 30 is a sprocket wheel 31 connected by a link belt 32 with the corresponding sprocket wheel 21 of the shaft 19. A pulley or other power wheel 33 is connected to the power shaft 34 and by means of a set of gears 35 the shaft 30 is driven from the power shaft 34. In this connection it will be apparent that many minor details of construction may be varied without departing from the spirit of the invention or sacrificing any of its advantages so long as the scope of the same as defined by the appended claims is maintained.

Having thus described the invention, what is claimed as new, is:

1. In a device of the character set forth, the combination of an upright tower, shafts journaled at the upper and lower corners of the rear of the tower, a shaft journaled at the top of the front of the tower, sets of three sprocket wheels secured to the ends of the shafts aforesaid, the sets lying in parallel planes, sprocket chains operating in said planes over said wheels, means for driving said chains, and a series of buckets extending between and secured to said chains, each bucket being provided with an automatic valve comprising a bolt having a head at one end and a nut at the other, the inner face of the head being provided with a plurality of projections adapted to engage the bottom of the bucket when the bucket is inverted.

2. The herein-described bucket for endless water conveyors comprising bottom, rear, front, and end portions, the top being open and the bottom being perforated and the perforation being fitted with an automatic valve consisting of a bolt passing through the perforation and having at one end a head and at the other end a nut, the head being provided on its inner face with a plurality of projections adapted to engage the bottom of the bucket in one position of the latter, and a gasket adjacent to said nut adapted to engage the bottom of the bucket in another position of the latter to close the perforation.

In testimony whereof I affix my signature in presence of two witnesses.

SAMUEL GARVIN.
